UNITED STATES PATENT OFFICE.

CLARE NELSON, OF BROOKLYN, NEW YORK, ASSIGNOR, BY MESNE ASSIGNMENTS, TO CHARLES C. ORCUTT.

PAPER-DRYING MACHINE

Application filed October 22, 1921. Serial No. 508,632.

To all whom it may concern:

Be it known that I, CLARE NELSON, a citizen of the United States, residing at Brooklyn, in the county of Kings, State of New York, have invented certain new and useful Improvements in Paper-Drying Machines; and I do hereby declare the following to be a full, clear, and exact description of the invention, such as will enable others skilled 10 in the art to which it appertains to make and use the same.

My invention is an improvement in drying machines, and relates particularly to an improved machine for drying paper, after 15 it has been coated by the methods set forth in application Serial No. 241,102, filed June 21, 1918, and application, Serial No. 492,932, filed August 17, 1921.

In carrying out these methods, a film of 20 moisture is first applied to one face of the sheet, and the said face is afterwards spattered with specks of color, one or more colors being used, and the colors are applied in succession to the same area, as in application, Serial No. 241,102, filed June 21, 1918, or simultaneously to the same area, as in application, Serial No. 492,932 filed Aug. 17, 1921. It is desirable in order to attain attractive and artistic effects, that the colors 25 be set quickly after blending, that is that the web of paper be quickly dried, thereby avoiding the danger of the colors running, as well as the need for supporting the paper for a relatively long time in festoons, as is the usual practice. In drying machines of 30 the character shown and described in applications, Serial No. 475,795 filed June 7, 1921, and Serial No. 477,422 filed June 14, 1921, a casing, or a series of casings, is provided, 35 through which the coated paper is drawn, moving on or with a suitable support, arranged within the casing, and extending the full length thereof. Air is circulated 40 through the casing, and heating means is arranged within the casing for heating the air as it circulates, to dry the paper. The casings are rectangular in transverse cross-section, providing thus an internal capacity in excess of that required for the proper circulation of the air and the passage of the 45 paper. The angles between the walls of the casing provide dead air pockets which impede the rapid changing of the air essential to quick drying, and the shape of

the casing results in an appreciable waste 55 of heat by convection and radiation.

The object of the present invention is to provide a construction of casing, such that heat losses through convection and radiation are greatly lessened, and all obstruction to the rapid and complete changing of the air is eliminated, and wherein the paper is quickly and thoroughly dried in a relatively brief time, and with a relatively small expenditure of fuel. 65

In the drawings;

Figure 1 is a longitudinal vertical section of one embodiment of the improved dryer,

Figure 2 is a transverse vertical section, 70

Figures 3 and 4 are views similar to Figure 1 showing alternate forms,

Figure 5 is a transverse vertical section of Figure 4.

In the embodiment of the invention shown 75 in Figure 1, a casing 1 is provided, of suitable length and cross-section, and the said casing is provided with inlet and outlet passages 2 and 3 at its opposite ends, through which the web 4 of paper may enter and leave the casing. The web of paper in its movement through the casing is supported by the upper run of an endless belt 5, of foraminous material, as for instance wire cloth. The upper run of the belt extends 80 through the passages 2 and 3, and is supported by rollers 6 journaled transversely of the casing, the rollers being arranged at suitable intervals to properly support the run and the web. The lower run of the belt 90 is below the casing, and outside of the casing the belt passes over rollers 7 arranged in such manner that the belt does not engage the casing, and may move freely with the paper web as it passes through the casing. Below 95 the casing tension rollers 8 are arranged, for tensioning the belt, and the web is drawn through the casing 1, by means of rollers 9 which grip the web beyond the casing.

Suitable means is arranged within the 100 casing for heating the air, the said means being in the present instance, electrically controlled heating means 10. The heating units are arranged adjacent to the outlet end of the casing, and extend from the said 105 outlet end about two-thirds the length of the casing. When the dryer is used for drying coated paper, for which it is especially de-

signed, the heating units need be arranged above the web only. When used for drying a paper web, as it leaves the wet end of a paper making machine, the heating means 5 will be arranged above and below the web. The dryer units may be arranged in the manner shown and described in application Serial No. 475,795, filed June 7, 1921, that is in series, one above the other, or they may 10 be arranged in series in alinement one with the other, or a single unit may be used. Means is provided for circulating air through the casing to be heated by the heating means, to dry the web, and to remove 15 the vapor as it forms. The said means comprises an air supply pipe 11, which delivers to the casing at the outlet end, above and below the web, by means of valved branch pipes 12. The pipe 11 may be connected 20 with a suitable circulating device, as for instance a pump or air compressor. The air is withdrawn by means of nozzles 13, arranged within the casing at the opposite end, and above and below the web. The nozzles 25 are connected with a collector pipe 15, by means of valved branch pipes 14.

In the usual construction of dryer units, the casings are rectangular in transverse cross-sections. This arrangement provides 30 corners which form dead air pockets, for the collection of vapor, which condenses at such points. In order to eliminate these pockets, I make the casing oval, or elliptical in cross-section as shown in Figure 2, and 35 the top of the casing is preferably of copper, which is polished on its inner face. The polished, arched shape acts as a reflector, throwing the heat onto the upper face of the web, thus utilizing the heat provided by the 40 heating means to the best possible advantage. The particular shape of the interior of the casing, offers the least possible impediment to the free circulation of air, and eliminates all pockets where vapor laden air 45 might collect.

If it is desired to constrain the web to take an arched formation as it passes through the dryer unit, as is desirable in treating certain grades of paper, as for instance heavy 50 paper board, the alternative arrangement shown in Figure 3 may be used. In this construction, the casing 16, which is of the same cross-section as that of Figure 1, is arched longitudinally, so that an arched formation 55 is given to the web during its passage through the dryer. In such construction, the web is supported by the belt 17 of foraminous material, whose upper run passes longitudinally of the casing, being 60 supported by rollers 18, to provide the arched formation. The web 19 is drawn through the casing by rollers 20, and the heating means is in the form of electrical units 21, arranged above the web, in the 65 same manner as the heating means 10 is

arranged in the casing 1. The elliptical or oval form is especially desirable for drying a paper web as it comes from the wet end of a paper making machine, the top and the bottom of the casing acting as reflectors. 70 In Figures 4 and 5 there is shown a construction wherein the top 21^a of the casing 22 is arched transversely. As shown more particularly in Figure 5, the bottom 75 of the casing is flat and plane. The web in its passage through the casing is supported by rods 23, which extend longitudinally of the casing, in spaced relation, the paper web 24 resting directly on the rods. The web is moved through the casing, by a pair of rollers 25, and the heating means 26, electrically controlled in the present instance, are arranged in the same manner as in Figures 1 and 3. In each construction, 80 the top of the casing is preferably of copper, or copper lined, and highly polished, to provide for a maximum of reflection.

Thus the top is a reflector, and cooperates with the source of heat, which is a source of radiant heat, reflecting the same upon the 90 paper.

I claim:

1. In a machine for drying paper, a casing through which the paper is adapted to be drawn, means for circulating air through 95 the casing, a source of radiant heat within the casing, and means in connection with the casing for reflecting the heat upon the paper to be dried.

2. In a machine for drying paper, a casing through which the paper is adapted to be drawn, means within the casing for supporting the paper in its passage through the casing, means for circulating air through 100 the casing, a source of radiant heat arranged within the casing above the paper for heating the air circulating through the casing, said casing having a transversely arched top 105 acting as a reflector for the heat.

3. In a machine for drying paper, a 110 casing through which the paper is adapted to be drawn, means within the casing for supporting the paper in its passage through the casing, heating means in the casing above the paper, and means for circulating air 115 through the casing to be heated and dried by the heating means, said casing being oval in transverse cross-section for the purpose specified.

4. In a machine for drying paper, a casing through which the paper is adapted to be drawn, means within the casing for supporting the paper in its passage through the casing, heating means in the casing above the paper, and means for circulating air through the casing to be heated and dried by the heating means, the top 125 of the casing being arched transversely and internally polished for the purpose specified.

5. In a machine for drying paper, a casing through which the paper is adapted to be drawn, means within the casing for supporting the paper in its passage through the casing, heating means in the casing above the paper, and means for circulating air through the casing to be heated and dried by the heating means, the casing being oval in transverse cross-section and having the top thereof polished internally for the purpose specified. 30
6. In a machine for drying paper, a casing through which the paper is adapted to be drawn, means within the casing for supporting the paper in its passage through the casing, means for circulating air through the casing, radiant heating means within the casing for heating the air, and a reflector above the radiant heating means for reflecting the heat upon the paper. 35
7. In a machine for drying paper, a casing through which the paper is adapted to be drawn, means within the casing for supporting the paper in its passage through the casing, means for circulating air through the casing, radiant heating means
- 10 15 20 25
- within the casing for heating the air and arranged above the paper, and a reflector above the radiant heating means for reflecting the heat upon the paper. 30
8. In a machine for drying paper, a casing through which the paper is adapted to be drawn, means for circulating air through the casing, a source of heat within the casing, and means in connection with the casing for reflecting the heat upon the paper to be dried. 35
9. In a machine for drying paper or the like, a casing through which the paper is adapted to be drawn, a source of heat 40 within the casing, and means in connection with the casing for reflecting the heat upon the paper to be dried.
10. In a machine for drying paper or the like, a casing through which the paper is adapted to be drawn, a source of radiant heat within the casing, and means in connection with the casing for reflecting the heat upon the paper to be dried. 45

In testimony whereof I affix my signature.

CLARE NELSON.
